Filed Sept. 1, 1970, Ser. No. 24,802

Term of patent 14 years

Int. Cl. D3—03

U.S. Cl. D88—3

FIG. 1

FIG. 2

FIG. 3

FIG. 4

FIG. 1 is a perspective view of the shade umbrella showing my new design;

FIG. 2 is a top plan view thereof;

FIG. 3 is a fragmentary bottom plan view of FIG. 1 on an enlarged scale; and

FIG. 4 is a side elevational view of FIG. 1.

The characteristic feature of this design relates to the slats which make up the shade umbrella and which are narrower at the center of the umbrella and become wider at the outer periphery thereof and to the position holding the slats together which have a constant width from the center of the umbrella to its periphery and extends both above the adjacent slats and below the adjacent slats so as to be visible both when viewed from above and from below the opened shade umbrella.

I claim:

The ornamental design for a shade umbrella, as shown.
